ATTORNEY.

UNITED STATES PATENT OFFICE.

SIDNEY JAMES, OF NIAGARA FALLS, NEW YORK, ASSIGNOR TO SIMEON L. AND
GEORGE H. ROGERS COMPANY, A CORPORATION OF MAINE.

DESIGN FOR A HANDLE OF A SPOON, A KNIFE, OR A FORK.

59,354.

Specification for Design.

Patented Oct. 11, 1921.

Application filed June 28, 1921. Serial No. 481,113. Term of patent 7 years.

To all whom it may concern:

Be it known that I, SIDNEY JAMES, a citizen of the United States, residing at Niagara Falls, in the county of Niagara and State of New York, have invented a new, original, and ornamental Design for a Handle for a Spoon, a Knife, or a Fork, of which the following is a specification, reference being had to the accompanying drawing, forming part thereof.

The figure is a front view of the handle for a spoon, knife or fork, showing my new design.

I claim:

The ornamental design for a handle of a spoon, a knife or a fork as shown.

SIDNEY JAMES.

In presence of—

OSCAR C. THEILER,
W. H. BROWNING.
